UNITED STATES PATENT OFFICE.

AMABLE LOZAI AND ACHILLE LERCIU, OF PETITE GUEVILLE, FRANCE.

COAL BREAKER.

Application filed June 1, 1926, Serial No. 113,034, and in France September 11, 1925.

The present invention relates to apparatus for breaking coal, coke and similar materials; and its object, stated briefly, is to provide, in a machine or apparatus of that character, 5 certain improved structural features or devices whereby the driving mechanism will be thrown out of operation automatically consequent upon the introduction of unbreakable bodies, such as stone, iron and the like, 10 into the machine with the coal.

According to the form of the invention now preferred, and as illustrated in the accompanying drawings, the material to be broken up is carried across a supporting 15 table which is normally held in raised position, but which is caused to yield and move down when the crushing implements encounter uncrushable material; and this yielding downward movement of the table is utilized to release a normally-locked or latched 20 member which thereupon acts to interrupt the drive. The invention involves these features not only in their broad aspect and in combination, but also in their specific details; 25 and it further involves various other combinations and arrangements of parts and features, as hereinafter described and claimed.

In said drawings, Figures 1 and 2 are, respectively, a side elevation and a left-hand 30 end view of the improved apparatus or machine, and Fig. 3 is an enlarged view of a detail of the latch mechanism.

Referring more particularly to the drawings, the apparatus, which is mounted on a 35 suitable base or bed, comprises a framework that embodies upright end members or standards A, A', connected at their lower portions by side members B, B', and at their upper portions by horizontal cross-ties C, C'; the 40 various parts being bolted or otherwise fastened together. The ties or auxiliary side members C, C', have their inner side faces provided with guideways for engagement by a pair of vertically-movable slides or cross-heads D, D', which, in turn, carry plates 45 F, F' on their under faces provided with holes to receive the shanks of the crushing or breaking tools G, G', here shown as in the form of vertically-arranged picks. There 50 are two distinct sets or groups of these picks, one set G' carried by the cross-head D and hereinafter called the roughing picks, and the other set G carried by the cross-head D' and termed the finishing picks; those of the 55 last-named set being adjustable laterally with relation to one another to regulate the size of

the pieces into which the coal or the like is to be broken.

To actuate the two sets of picks in alternation at the proper intervals, a shaft H 60 is provided having two suitably-positioned cranks connected by rods or pitmen E, E' with spindles M, M', mounted upon the cross-heads D, D'. The crank shaft is journaled in bearings I, I' secured to the tops of the 65 standards A, A', and it carries at one end fast and loose pulleys T and U with which a driving belt (not shown) is alternatively engageable, being shiftable from one to the other by a fork Y', as hereinafter explained. 70 The reciprocatory movement of the picks carries them toward and from a breaking or crushing table J, over which passes an endless conveyor N consisting of a series of metal plates attached at opposite ends to a pair of 75 sprocket chains that travel around pairs of sprockets O, O' secured to horizontal cross-shafts P, P'. The rear shaft P is connected to be driven from an upper cross-shaft P': in the present instance, by means of a chain 80 T' and sprockets T² and T³ secured, respectively, to the shafts P' and P; the former shaft also being provided with a bevel gear S' in mesh with and driven by a bevel pinion S which is fixed to the opposite end of 85 a crank shaft H from pulleys T, U. Shafts P and P' are journaled in brackets Q and R secured to standard A, while shaft P' is similarly journaled in brackets Q' secured to the 90 front standard A'.

So far as concerns the parts already described, the operation is believed to be obvious. Assuming that the driving belt is engaged with the fast pulley T, the crank shaft H will be rotated and will act to reciprocate the two sets of picks, one after the other, which thus move toward and from the material to be crushed. At the same time, the belt or conveyor N which carries the material beneath the picks is driven from shaft H 100 through the gearing S, S', and the chain-and-sprocket connection T²—T'—T³.

The main feature of the invention, however, is the provision of an automatic throw-out which is operated whenever one set of 105 picks—in this case, the roughing picks G'—encounter unbreakable material on the conveyor; the arrangement being such that when that contingency occurs, the drive will be automatically discontinued or interrupted 110 and the shaft H will cease to rotate. Preferably, this interrupting action is effected by

shifting the driving belt onto the loose pulley; the shifting fork Y' being spring-loaded to move the belt when released from a locking or latching device which normally holds it in cocked position. The crushing table J whereover the upper stretch of conveyor N passes, is mounted to yield when the picks strike unbreakable material on the conveyor, and it is this yielding movement which is utilized to release the latch.

According to the construction illustrated, table J is hinged or pivoted at its rear end upon a horizontal rod or pin L mounted in bearings in the rear standard A, and is supported adjacent its front end by a pair of springs K which normally hold that end raised and which are positioned in recesses in the lower or main side members B, B' of the framework. The springs K actually engage the ends of a cross-rod L' whereon the table directly rests, and it will be apparent that said springs will necessarily yield when the downward pressure exerted by picks G' exceeds their upward pressure.

25 The previously-mentioned shifting fork Y' includes as a part thereof a horizontal shaft or rod Y carrying an expansible coil spring Z' that tends to move it in a direction to shift the belt from the fast pulley to the loose pulley; said rod being slidably mounted in openings formed through a pair of spaced cheeks or lugs V, V', which are here shown as carried by one of the upper or auxiliary side members or ties (in this case, member C'). A cross-pin X' is also mounted in lugs V, V', and constitutes a pivot for a lever X which is connected at its outer end by a chain Z, or other flexible element to the adjacent end of cross-rod L'; the other end of the lever being adapted to catch into a notch or shoulder Y² formed in the fork rod Y and disposed in the space between said lugs when the fork is retracted to engage the driving belt with the fast pulley T.

45 Due to this arrangement, it will be apparent that the downward movement of the crushing table J described above will exert a downward pull on chain Z, with the result that the catch or lever X will turn clockwise about its pivot X', and its inner arm will be released from the notch Y² in rod Y. Spring Z' will thereby be freed and its expansion will move the fork to the right; said fork carrying the driving belt onto the loose pulley U and in consequence, terminating the rotation of shaft H, whereupon the machine will cease operating. After removal of the unbreakable material from the machine, the latter can be re-started by retracting the fork in any desired manner so as to bring the driving belt back again to engagement with the fast pulley, the rearward or leftward movement of the fork compressing its actuating spring Z' and finally bringing the notch Y² into line with the inner arm of the catch lever X which

will fall into it of its own weight. The springs K, of course, will restore table J to its normal raised position.

We claim as our invention:

1. A breaking machine for coal and the like, comprising a main shaft; fast and loose pulleys mounted thereon for alternative engagement by a driving belt; crushing tools carried by said shaft; a belt shifter; and means for automatically operating the belt shifter to engage the belt with the loose pulley when the crushing tools strike unbreakable material.

2. A breaking machine, comprising a yieldingly mounted element to support the material being crushed; crushing tools operative on the material on said support and acting to cause yielding movement of the same on contact with unbreakable material; means for operating said tools; and means operated automatically consequent upon such yielding movement for terminating the action of the tool-operating means.

3. A breaking machine, comprising a yieldingly mounted element to support the material being crushed; a crank shaft extending thereover; crushing tools suspended from said shaft for operation on the material on said support and acting to cause yielding movement of the same on contact with unbreakable material; driving means for said shaft; and means operated automatically consequent upon such yielding movement for terminating the action of said driving means.

4. A breaking machine for coal and the like, comprising a crankshaft; crushing tools suspended therefrom; driving means for said shaft; and mechanical means operating automatically and positively to terminate the action of said driving means consequent upon contact of said tools with unbreakable material.

5. A breaking machine, comprising a yielding support for the material to be crushed; a main shaft extending thereover; crushing tools carried by said shaft and acting to cause yielding movement of said support on contact with unbreakable material; fast and loose pulleys mounted on said shaft for alternative engagement by a driving belt; a belt shifter; and means operated automatically consequent upon the yielding movement of the support for actuating the belt shifter to engage the belt with the loose pulley.

6. A breaking machine according to claim 2, in which the support is hinged at one end for swinging movement, and in which spring means are provided for normally holding the other end of the support in raised position.

7. A breaking machine, according to claim 5, in which the support is hinged at one end for swinging movement, and in which spring means are provided for normally holding the other end of the support in raised position.

8. A breaking machine, comprising a main

shaft; fast and loose pulleys mounted thereon for alternative engagement by a driving belt; a spring-loaded belt shifter tending to engage the belt with the loose pulley; a latch for holding the belt shifter in cocked position with the belt engaging the fast pulley; crushing tools carried by said shaft; and means for automatically releasing the latch when the crushing tools strike unbreakable material.

9. A breaking machine, comprising a yielding support for the material to be crushed; a main shaft extending thereover; crushing tools carried by said shaft and acting to cause yielding movement of said support on contact with unbreakable material; fast and loose pulleys mounted on said shaft for alternative engagement by a driving belt; a spring-loaded belt shifter tending to engage the belt with the loose pulley; a latch for holding the belt shifter in cocked position with the belt engag-

ing the fast pulley; and means operated automatically consequent upon the yielding movement of the support for releasing the latch.

10. A breaking machine, comprising a main shaft; fast and loose pulleys mounted thereon for alternative engagement by a driving belt; a belt shifter; means tending to move the belt shifter in a direction to engage the belt with the loose pulley; means acting against the last-named means to hold the belt shifter in a position in which the belt engages the fast pulley; crushing tools carried by said shaft; and means for automatically releasing said holding means when the crushing tools strike unbreakable material.

In testimony whereof we affix our signatures.

LOZAI, AMABLE.
LERCIU, ACHILLE.
